UNITED STATES PATENT OFFICE.

ANTON GOTTFRIED, OF ERIE, PENNSYLVANIA.

ORGAN-PIPE.

No. 872,931.

Specification of Letters Patent.

Patented Dec. 3, 1907.

Application filed August 9, 1906. Serial No. 329,859.

To all whom it may concern:

Be it known that I, ANTON GOTTFRIED, a citizen of the United States, and a resident of Erie, in the county of Erie and State of Pennsylvania, have invented a new and Improved Organ-Pipe, of which the following is a full, clear, and exact description.

The object of the invention is to provide a new and improved organ pipe arranged to respond quickly and positively to the sheet of wind, and to allow of obtaining different tonal qualities in a simple manner.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a sectional side elevation of the improvement; Fig. 2 is a face view of the same; Fig. 3 is an enlarged sectional plan view of the same on the line 3—3 of Fig. 1; Fig. 4 is an enlarged sectional side elevation of the same; Figs. 5 and 6 are sectional plan views of modified forms of the body of the organ pipe, and Fig. 7 is a side elevation of an organ pipe having a tapering body.

The body A of the organ pipe is made of suitable material and is given any desired shape, and the said body A terminates at its lower end in the foot B having the usual air inlet C. The languid D at the junction of the body A with the foot B has its front edge provided with two bevels D' and D² extending in opposite directions from a common apex D³, that is, the top bevel D' extends upwardly and inwardly into the body A, and the lower bevel D² extends downwardly and inwardly into the foot B, as plainly indicated in Figs. 1 and 3. The lower bevel D² is preferably nicked or serrated and is disposed opposite the similarly nicked or serrated lower lip E of the foot B, and the upper bevel D' is at the mouth F and a short distance from the front plate G of the body A. The bottom of the languid is slightly curved upwardly or convex at the rear portion, and the top of the languid is hollowed out or concaved and is rendered gradually thinner from the front beveled edge to the rear end, see particularly Fig. 4. The outer or inner face of the front plate G is beveled adjacent to the mouth F, and the front plate G is flat

throughout the length of the pipe and is made thicker than the remaining side and rear portions of the body A, as will be readily understood by reference to Figs. 3, 5 and 6. 60

The depth and cross sectional shape of the body A vary for producing different tonal effect; thus for obtaining a very powerful and reedy tone a deep body A, such as shown in Fig. 3, is selected, and which body 65 is capable of carrying a large volume of wind and capable of strong vibrations. Other styles of body are selected for giving different characters, such as reedy, stringy, dull, fresh, loud, soft, mellow, etc. Thus a pipe 70 having a body as shown in Fig. 5 is for producing a moderate reedy tonal quality and a pipe having a body as shown in Fig. 6 is for producing a mellow tonal quality.

It is expressly understood that the front 75 plate G acts as a lip and owing to its being flat leaves to the column of wind free sway without obstruction, such as found in the old style upper and lower lip organ pipe.

The organ pipe is provided with the usual 80 dowel beard H forming an auxiliary device for the voicer, to regulate the direction of the wind. The dowel beard H is attached to the ears I extending forward on opposite sides of the body A. The upper end of the body A 85 is provided with the usual tuning flap J.

By the arrangement described the organ pipe takes the place of a reed pipe, and one of the main advantages of the construction shown and described is that a number of different tonal qualities may be readily obtained by changing the size and shape of the body to suit or imitate such tonal qualities as are produced by the trombone, oboe, saxaphone, trumpet, clarinet, clarion, or other like 95 instruments.

The organ pipe can be readily made in any pitch or foot number, as 16 foot, 8 foot, 4 foot, 2 foot and 1 foot, with equally good results. The body A of the pipe may be put 100 together either in one or more sections and all such parts may be made of different metals and of different thicknesses.

Having thus described my invention, I claim as new and desire to secure by Letters 105 Patent:

1. An organ pipe having a languid provided with a thickened and double beveled front edge.
2. An organ pipe, comprising a body, a 110 foot, a concavo-convex languid having a thickened and double beveled front edge to

direct the sheet of wind directly against the upper front plate, the lower bevel of the languid being nicked.

3. An organ pipe, comprising a body, a 5 foot, and a languid having a double beveled front edge to direct the sheet of wind directly against the upper front plate, the underside of the languid being convex at the rear and the top of the languid being hollowed out.

4. An organ pipe, comprising a body, a 10 foot, and a languid having a double beveled front edge to direct the sheet of wind directly against the upper front plate, the latter being flat throughout its length and beveled at 15 its lower end and in the direction of its length.

5. An organ pipe, comprising a body, a 20 foot having a nicked lip, and a languid having a double beveled front edge to direct the sheet of wind directly against the upper front plate, the lower beveled portion of the languid being nicked and arranged opposite the nicked surface of the lip of the foot.

6. An organ pipe having a body curved in 25 cross section and provided with a flat front plate extending throughout the length of the body.

7. An organ pipe having a body curved in 30 cross section and provided with a flat front plate of greater thickness than the curved portion of the body.

8. An organ pipe, comprising a body

curved in cross section and having a flat front plate of greater thickness than the 35 curved portion of the body, and a languid having a double beveled front edge and gradually decreasing in thickness from the front edge to the rear.

9. An organ pipe, comprising a body 40 curved in cross section and having a flat front plate of greater thickness than the curved portion of the body, a foot having a serrated lip, and a languid having a double beveled front edge, the lower bevel being 45 nicked, the underside of the languid being convex at the rear and the top thereof hollowed out, the languid gradually decreasing in thickness from the front to the rear.

10. An organ pipe, comprising a body having an especially long flat front plate and a rounded-off rear portion, a foot having a long flat lower lip, and a languid provided with a double beveled front edge, the underside of the languid being convex at the rear and the top of the languid being concave; the languid being made gradually thinner 55 from the front edge to the rear.

In testimony whereof I have signed my name to this specification in the presence of 60 two subscribing witnesses.

ANTON GOTTFRIED.
